UNITED STATES PATENT OFFICE.

JOHN LULEK, OF CICERO, ILLINOIS.

MAIL-BAG CATCHING AND DELIVERING APPARATUS.

1,142,107.

Specification of Letters Patent.

Patented June 8, 1915.

Application filed August 19, 1914. Serial No. 857,537.

To all whom it may concern:

Be it known that I, JOHN LULEK, a subject of the Emperor of Austria-Hungary, residing at Cicero, in the county of Cook 5 and State of Illinois, have invented certain new and useful Improvements in Mail-Bag Catching and Delivering Apparatus, of which the following is a specification.

This invention relates to certain new and 10 useful improvements in mail bag catching and delivering apparatus.

An object of the present invention is to provide a mail bag catching and delivering apparatus for railroads in which the mail 15 may be delivered from a moving car at a desired station or point on the road and other mail collected while the car is still in operation.

A further object of the invention is to 20 provide a mail catching and delivering apparatus for railroads in which the mail bag on a moving car may be delivered to the desired station by operating suitable mechanism to project the bag or bag receptacle in 25 the path of receiving apparatus and to utilize the same mail-delivering arm for the collection of other mail.

With the above and other objects in view 30 that will appear as the nature of the invention is better understood, the same consists in the novel construction, combination and arrangement of parts as will be hereinafter more fully described and then claimed.

In the accompanying drawings forming a 35 part of this application and to which reference is had herein by like characters designating corresponding parts throughout the several views:—Figure 1 is a side elevational view of the track-receiving and delivering mechanism. Fig. 2 is a top plan view of the same, illustrating the position of the receiving and delivering mechanism with respect to the track. Fig. 3 is a side elevational view with the car omitted to 40 illustrate the manner of removing the bag or bag receptacle from its support. Fig. 4 is a side elevational view of the delivery rack with a bag receptacle in position thereon. Fig. 5 is a cross-sectional view of a mail car 45 illustrating the collecting and delivery mechanism. Fig. 6 is a horizontal sectional view of a portion of the car, showing in top plan view the mail collecting and delivering mechanism. Fig. 7 is a front elevational 50 view of the mail bag receptacle. Fig. 8 is a top plan view of the same. Fig. 9 is a ver-

tical cross-sectional view of the receptacle, and, Fig. 10 is a detail sectional view of the receptacle in position on one of the tracks.

Briefly described, the invention consists in 60 providing a mail catching and delivery mechanism for railroads in which the mail within a moving car may be delivered at the desired station by suitable mechanism on the car and adjacent the track. I have also 65 provided means for collecting the mail which consists in providing an operating device adjacent the track to engage the mail holding arm on the car to correctly position the arm to pick up the waiting mail. 70

Referring more in detail to the accompanying drawings, the reference numeral 10 designates a mail car of any suitable construction provided with a side door opening 11. The mail catching and delivery mechanism carried by the car 10 comprises in detail a pair of spaced shafts 12 arranged transversely of the car 10 and on which is adapted to slide the arm for collecting and delivering the mail. A pair of bracket arms 13 have a loose connection at their ends as at 14 to the shafts 12. Hand grips 15 are carried by suitable ones of the shaft connections 14 and by which the members may be moved over said shafts. An arm 16 is fixed at its inner ends in central bearings 17 provided therefor intermediate the ends of the bracket arms 13 and intermediate the said bracket arms, the shaft 16 has connected thereto one end of a flat band spring 18 while the other end of said spring is connected to a sliding block 19 positioned on one of the shafts 12. The spring 18 is adapted to hold the arm 16 in a desired position for purposes to be later described. 90

The outer end of the arm 16 is provided with a pair of opposed arms 20 in which is journaled a guide roller 21. A mail bag or receptacle-holding device is carried by the outer end of the arm 16 opposite the said arms 20, and consists of a substantially U-shaped member 22 having the upper ends thereof outwardly flared as at 23 and hinged at its lower end as at 24 to said arm 16. A lug 25 is carried by one arm of the member 22 and has connected thereto one end of a coil spring 26, the opposite end of which is connected to the said arm 16 and adapted to hold the member 22 in the position shown in full lines in Fig. 5 and to return the said member to such position as shown by dotted lines in said figure. 100

The mail bag receptacle is shown in detail in Figs. 7 to 10 and consists of a box-like structure 27 having an open front end 28 for the reception of mail bags and the like and further provided with a cut-away portion 29 in the upper front wall thereof to provide a clearance for the ring 30 and plunger 31 for supporting said ring, which plunger is spring-retracted as at 32. An arm 33 extends upwardly from the top wall of the receptacle 27 and is provided at its upper end with lateral ears 34 in which are journaled the guide rollers 35. The upper end of the arm 33 extends rearwardly and downwardly as at 36 to provide a hanger or guide arm.

The mechanism arranged adjacent the track and operating in connection with the mail bag receptacle supporting mechanism above described, is shown in detail in Figs. 1 to 4 to be positioned adjacent the railroad track A. The frame-work or guide track 37 is supported on the standards 38 and provides a support for the mail receptacle 27 as clearly illustrated in Fig. 1. An operating device for the receptacle supporting member 22 is provided in the form of a track or guide 39 over which the guide roller 21 is adapted to move as shown in Fig. 3.

The mail delivery track is more clearly shown in detail in Fig. 4 and consists of the guide track 40, the fore-part of which is slightly inclined upwardly and then downwardly as shown in said figure, with the end of said track directed into a mail house B.

After the mail matter has been placed within the receptacle 27, the said receptacle has its cushioning ring 30 positioned on the outer leg of the U-shaped supporting member 22, and the arm 16 and mail receptacle 27 carried thereby are moved outwardly of the car as shown in Fig. 5, by shifting the cross brackets 18. The guide rollers 35 and hanger 36 are positioned to be placed on the track 40 and by the momentum of the car moved up the initial incline and travel on the curved portion 40' in a downward direction, at which time the U-shaped member 22 will be moved to dotted line position as shown in Fig. 5 to free the receptacle ring 30 therefrom, so that the mail receptacle may be delivered into the mail house B.

In collecting mail, the receptacle 27 is positioned on the track 37 and the guide roller 21 carried by the arm 16 caused to engage the guide track 39 to rotate the arm 16 against the tension of the band spring 18 to the position shown in Fig. 3, so that the U-shaped member 22 will be in position as shown in said figure to engage the ring 30. When the guide roller 21 leaves the track 39, the spring 18 will immediately return the member 22 to its normally vertical position, and further movement of the car will cause the rollers 35 to move over the track 37 and be freed therefrom and wholly supported by

the arm 16 so that the receptacle may be moved within the car 10.

It is believed from the above description that the operation of the device will be readily apparent and while I have shown and described the preferred embodiment of my invention, I do not wish to confine myself to the exact details of construction shown, as various forms, modifications and arrangements of the parts may be made without departing from the spirit and scope of the invention as claimed.

What I claim as new is:—

1. In a device of the class described, a pair of spaced shafts, bracket arms slidably mounted at their ends on said shafts, an arm journaled intermediate the ends of said bracket arms, a normally vertical supporting member on the outer end of said arm, means for causing said supporting member to assume a horizontal position, and means for returning said supporting member to its normally vertical position.

2. In a device of the class described, the combination with a car provided with transverse shafts, of bracket arms slidably mounted on said shafts, an arm journaled in said bracket arms, a normally-projecting U-shaped receptacle supporting member carried by the outer end of said arm, a guide roller carried by the outer end of said arm, a track over which said guide roller is adapted to travel to cause said U-shaped member to assume a horizontal position, and means for causing said U-shaped member to return to normally vertical position when said guide roller leaves said track.

3. In a device of the class described, guide members, a bracket adjustably mounted on said guide members, an arm journaled in said bracket, means associated with said arm and guide members for causing said arm to return to normal position when revolved in its journaled bearing, bag-supporting means carried by the outer end of said arm, and operating means for causing said arm to rotate to lower the bag-supporting means.

4. In a device of the class described, a pair of parallel shafts, a bracket slidably mounted thereon, an arm rotatably mounted in said bracket, a mail catching member pivoted to the outer end of said arm, a spring for holding the same normally vertical, a track, means carried by said arm adapted to engage said track to cause said arm to revolve and lower the mail catch member, and means associated with said shafts and arm to return said arm to its initial position.

5. In a device of the class described, a pair of guide members, an arm adjustably supported relative to said guide members, track-positioned means adapted to engage said arm to partially rotate the same, and means associated with said arm and guide

members adapted to restore said arm to its initial position.

6. In a device of the class described, a car, three spaced parallel arms positioned transversely of said car, one of said arms being adjustably associated with the other two arms, means for partially rotating said adjustable arm, and means for restoring said arm to its initial position.
- 10 7. In a device of the class described, the combination with a car having a side opening, of an arm adjustably mounted transversely of said car and adapted to be pro-

jected through said opening, a normally vertical bag-catching member carried by 15 said arm, means engaging said arm to cause the bag-catching member to assume a horizontal position, and means for returning said bag-catching member to vertical position.

20 In testimony whereof I affix my signature in presence of two witnesses.

JOHN LULEK.
